UNITED STATES PATENT OFFICE

2,474,993

PHONOGRAPHIC TRANSDUCER DEVICE

George C. Tibbetts, Camden, Maine, assignor to
Tibbetts Laboratories, a corporation of Maine

Application November 29, 1945, Serial No. 631,681

4 Claims. (Cl. 274—37)

1

In some phonograph apparatus the movement of the needle is predominantly in the direction of the vertical dimension or depth of the groove but usually the movement is back and forth in the direction of the crosswise dimension of the groove. In either case only the vibration in one direction should be transmitted to the transducer. For example if the recording is of the type in which the movement is intended to be in the direction corresponding to the width of the groove, transmission to the transducer of movement in the other dimension of the groove introduces distortions.

Objects of the present invention are to produce a phonographic device, which confines the effective movement of the needle substantially to one of the aforesaid dimensions of the groove, which is light and compact, which can be manufactured easily and economically, which minimizes harmonic distortion and surface noise, which affords a high order of fidelity, which permits easy regulation of frequency response, and which is generally superior to phonographic devices of the prior art.

According to the present invention the device comprises a needle support which transmits to the transducer movement along one dimension of the groove without permitting substantial transmission to the transducer of movement in the other dimension, in combination with a transducer movable back and forth and means interconnecting the support and transducer for movement back and forth in unison. Preferably the support has a flexible portion on one or both sides of the needle axis which permits swinging movement of the needle. In the preferred embodiment the needle support permits movement transversely of the record groove but is relatively immovable in a direction perpendicular to the surface of the record. The support may be made more flexible in one dimension than the other by making it thinner in one dimension. In the specific embodiment hereinafter described the support comprises a flat bar and means for rigidly supporting the bar at each end, the bar having a flexible portion between the needle and each of the supporting means and each flexible portion having a dimension lengthwise of the needle which is greater than its dimension crosswise of the needle, whereby back and forth movement of the needle produces torsional or twisting movement of the support or vice versa.

For the purpose of illustration typical embodiments of the invention are shown in the accompanying drawings in which

2

Fig. 1 is a top plan view of one embodiment; Fig. 2 is a section on line 2—2 of Fig. 1; Fig. 3 is a top plan view of another embodiment; and

5 Fig. 4 is a section on line 4—4 of Fig. 3. The particular embodiment of the invention shown in Figs. 1 and 2 comprises a casing 1 which is preferably formed of Bakelite or other similar insulating material, a phonographic transducer 2, which may be like that disclosed in my co-pending application Serial No. 570,361 filed December 29, 1944, now Patent No. 2,403,692, issued July 9, 1946, and a support 3 for the needle 4. The transducer 2 is mounted in the casing by 10 means of resilient blocks 6 of rubber or other yielding material. The blocks are cemented or otherwise secured to the bottom of the transducer and they are also preferably cemented to the bottom of the casing 1. The needle support 3 comprises an elongate bar having a thick central portion and relatively thin ends which are secured to the casing by means of bolts 7. Intermediate the thick central portion and the thin left end is a socket 8 having its axis inclined 15 at the usual angle to which phonograph needles are inclined. While the needle 4 may be mounted in the socket in any suitable way, as illustrated in the drawings it is mounted by means of two plugs 9 and 10 of rubber or other suitable material which are preferably under radial compression. Intermediate the socket 8 and the side wall of the casing 1 is another block 11 of rubber or other yielding material adapted to damp the vibrations of the bar 3, the block 11 being cemented to the outer surface of the socket or to the inner surface of the casing or to both. Extending laterally from the bar 3 is a short arm 12 which is connected to the transducer through the medium of a vertical rod 13 which may be cemented or otherwise secured to the arm and to the transducer. While the rod 12 is preferably rigid it may be formed of rubber so as to be somewhat yielding. The casing 1 has vertical openings 5 to receive bolts or other fastening means for mounting the device on the tone arm of the phonograph or the like. When mounting the needle in the semi-permanent manner of Figs. 1 and 2, the needle preferably has a sapphire or other durable point. The rod 13 may be flattened so that its cross-sectional dimension lengthwise of the bar 3 is greater than its dimension crosswise of the bar 2.

The modification shown in Figs. 3 and 4 is similar to the embodiment of Figs. 1 and 2 except in that the needle 14 is removably mounted

in the socket 18 by means of a screw 19 extending along a slot in the left-hand end of the bar 23 and threading into a boss 20 on the side of the socket 18. In each of the embodiments a plate 24 is preferably mounted on the bottom of the casing to limit the movement of the needle in case the projecting end of the needle is struck accidentally. The plates 24 have openings wide enough to permit normal vibration of the needles without contact between the two. In each embodiment leads 25 and 26 are connected to the terminals of the transducer for the purpose of connecting the device in circuit.

In following a groove which moves the needle sidewise, the supporting bar is twisted back and forth in the thin portions at each end, thereby causing the arm 12 to move up and down. This up and down movement is transmitted through the rod 13 to the transducer 2 which causes the transducer to vary the current in its circuit in the usual way. Variations of current through the transducer 2 moves the rod 13 up and down and in turn this causes the needle to swing laterally because of the torsional movement of the bars 3 and 23. Up and down movement of the needle has little if any effect on the transducer because of the rubber plugs 9 and 10 and because of the relatively large vertical dimension of the bar 3 and 14. By mounting the plugs 9 and 10 under radial compression the radial movement of the needle relatively to the bar is minimized without correspondingly reducing the freedom of movement of the needle lengthwise of its axis. Thus the device functions with minimum harmonic distortions and minimum surface noise, affording a high order of fidelity.

The peak frequency of the device may be predetermined by the mass of the needle support, the mass of the needle, the modulus of elasticity of the material from which the needle support is made, the length of the thin portions of the needle support, the thickness and width of the thin portions of the needle support, and the characteristics of the transducer 2, its supporting pads 6, and the damping block 11.

It should be understood that the present disclosure is for the purpose of illustration only and that this invention includes all modifications and equivalents which fall within the scope of the appended claims.

I claim:

1. A device of the character referred to comprising a needle adapted to trace a record groove, a needle support which permits movement transversely of said groove but which is relatively immovable in a direction perpendicular to the surface of the record, a transducer capable of back and forth movement, and means interconnecting said support and transducer so that one of said movements produces the other movement, said support comprising a bar and means for rigidly supporting the bar at each end, the bar having a thin portion between the needle and each of said

supporting means and each thin portion having flexibility which is greater crosswise of the needle than lengthwise of the needle.

2. A device of the character referred to comprising a needle adapted to trace a record groove, a needle support which permits movement transversely of said groove but which is relatively immovable in a direction perpendicular to the surface of the record, a transducer capable of back and forth movement, and means interconnecting said support and transducer so that one of said movements produces the other movement, said support comprising a bar and means for rigidly supporting the bar at each end, the bar having a flexible portion between the needle and each of said supporting means and each flexible portion having a dimension lengthwise of the needle which is greater than its dimension crosswise of the needle.

3. A device of the character referred to comprising a needle adapted to trace a record groove, a needle support which permits movement transversely of said groove but which is relatively immovable in a direction perpendicular to the surface of the record, a transducer capable of back and forth movement, and means interconnecting said support and transducer so that one of said movements produces the other movement, said support comprising a flat bar and means for mounting the needle with its axis extending edgewise of the bar, said means comprising elastic material which permits movement of the needle relatively to the bar endwise of the needle.

4. A device of the character referred to comprising a needle adapted to trace a record groove, a needle support which permits movement transversely of said groove but which is relatively immovable in a direction perpendicular to the surface of the record, a transducer capable of back and forth movement, and means interconnecting said support and transducer so that one of said movements produces the other movement, said support comprising a flat bar and means for mounting the needle with its axis extending edgewise of the bar, said means comprising elastic material which permits movement of the needle relatively to the bar endwise of the needle, said material being compressed radially of the needle to minimize radial movement of the needle relatively to the bar.
